US0D1007457S

(12) **United States Design Patent** (10) Patent No.: **US D1,007,457 S**
(45) Date of Patent: ** Dec. 12, 2023

(54) **TRANSCEIVER FOR THE WIRELESS MICROPHONE SYSTEM**

(71) Applicant: **Catchbox SIA**, Riga (LV)

(72) Inventors: **Pyry Valtteri Taanila**, Riga (LV);
Mikelis Studers, Riga (LV); **Toms Cirvelis**, Riga (LV)

(73) Assignee: **Catchbox SIA**, Riga (LV)

(**) Term: **15 Years**

(21) Appl. No.: **35/514,224**

(22) Filed: **Mar. 16, 2022**

(80) **Hague Agreement Data**

Int. Filing Date: **Mar. 16, 2022**

Int. Reg. No.: **DM/220374**

Int. Reg. Date: **Mar. 16, 2022**

Int. Reg. Pub. Date: **May 6, 2022**

(57) **CLAIM**

The ornamental design for a transceiver for the wireless microphone system, as shown and described.

DESCRIPTION

1. Transceiver for the wireless microphone system

1.1 : Perspective

1.2 : Top

1.3 : Front

1.4 : Back

1.5 : Left

1.6 : Right

1.7 : Perspective

1.8 : Bottom

The broken lines shown in the drawings represent unclaimed portions of the article and form no part of the claimed design.
